UNITED STATES PATENT OFFICE.

FRED E. FLACK, OF URSA, ILLINOIS.

BRICKMAKING-MACHINE.

1,149,747.

Specification of Letters Patent. Patented Aug. 10, 1915.

Application filed March 5, 1915. Serial No. 12,355.

To all whom it may concern:

Be it known that I, FRED E. FLACK, a citizen of the United States, residing at Ursa, in the county of Adams and State of Illinois, have invented a new and useful 5 Brickmaking-Machine, of which the following is a specification.

The device forming the subject matter of this application is adapted to be employed 10 in the making of concrete bricks although articles other than bricks may be manufactured in the structure therein disclosed.

The invention aims to provide a novel mechanism which, being reciprocated, travels beneath a scraping or troweling means and a compressing means, both of which means coact with the material in the mold.

Another object of the invention is to provide novel means whereby the mold may be 20 moved readily from a reciprocating carriage by simply trundling the mold supporting auxiliary carriage off the main carriage onto an auxiliary track.

Another object of the invention is to provide 25 novel means for reciprocating the main carriage.

A further object of the invention is to improve the construction of those elements which serve to scrape, trowel down and 30 press the aggregate with respect to the mold.

It is within the scope of the disclosure to improve generally and to enhance the utility of devices of that type to which the present invention appertains.

35 With the above and other objects in view which will appear as the description proceeds, the invention resides in the combination and arrangement of parts and in the details of construction hereinafter described 40 and claimed, it being understood that the changes in the precise embodiment of the invention herein disclosed can be made within the scope of what is claimed, without departing from the spirit of the invention.

45 In the accompanying drawings:—Figure 1 shows the invention in side elevation, parts being broken away; Fig. 2 is a transverse section; Fig. 3 is a perspective disclosing the housing or casing in which the pressure roller is located; Fig. 4 is a transverse sec-

tion taken through the pressure roller and its housing or casing; Fig. 5 is a perspective showing one of the bearings; Fig. 6 is a fragmental vertical section of the structure shown in Figs. 3 and 4; Fig. 7 is a perspective showing one of the mold forming elements; Fig. 8 is a perspective showing another of the mold forming elements; Fig. 9 is a fragmental top plan of the mold.

In carrying out the present invention 60 there is provided a supporting structure denoted generally by the numeral 1 and embodying a main track 2. The supporting structure includes auxiliary tracks 3 and 4, the tracks being spaced from each other at 65 a considerable distance and being elevated above the main track 2.

The invention comprises a reciprocating main carriage 5 provided with wheels 6 adapted to traverse the main track 2, the 70 main carriage 5 being mounted to move toward and away from the auxiliary tracks 3 and 4. The main carriage 5 is provided with a longitudinally extended track 7 and supported on the main carriage between the 75 constituent rails of the track 7 is a drip pan 8.

An auxiliary carriage is mounted to reciprocate at times with the main carriage 5 and at times is adapted to move upon the 80 main carriage, the auxiliary carriage being denoted by the reference character 9. The auxiliary carriage 9 is provided with wheels 10 adapted to traverse the track 7 on the main carriage 5.

85 Although the weight of the auxiliary carriage and parts carried thereby ordinarily is sufficient to prevent the auxiliary carriage from moving on the main carriage during the reciprocation of the latter, any suitable 90 and simple means may be provided for positively preventing the auxiliary carriage from moving on the main carriage when the latter is reciprocated. For this purpose, the main carriage 5 may carry movable dogs 11 95 adapted to coact with the wheels 10 of the auxiliary carriage 9.

100 Mounted upon the auxiliary carriage 9 is a mold which may be of any desired form. The mold, denoted by the numeral 12 is in

the present instance shown as being removable and collapsible, the mold comprising base strips 14 having upstanding cross walls 15, division strips 16 located between the 5 base strips 14 and coacting with the cross walls 14, end walls 17, and side walls 18, any suitable means indicated conventionally at 19 being employed for holding the mold in operative condition.

10 Presupposing that the structure is to be employed in the making of concrete bricks, it will be noted that the mold above described is so fashioned that it comprises a plurality of cells, in each of which a brick 15 is adapted to be formed.

10 Fixed to and rising from the sides of the supporting structure 1 are standards 20 having openings or slots 20^a in which are mounted for vertical reciprocation but 20 against rotation, rectangular bearings 21 having journaling openings 22. The bearings 21 are depressed yieldingly by means of springs 23, the lower ends of which engage the bearings, the upper ends of which 25 are engaged by hand screws 24 or other suitable adjusting means mounted in the upper portions of the standards 20. Each bearing 21 is provided with a segment 27.

15 The invention includes an arched casing 30 28 provided at its ends with tubular shafts 29 which are mounted for rocking movement in the openings 22 of the bearings 21.

20 In order that the casing 28 may be rocked in the bearings 21, the casing is provided 35 with a lever 30, and in order to hold the casing in adjusted positions, the lever 30 carries a latch mechanism 31 of any desired sort 40 adapted to coöperate with the segment 27.

Secured adjustably to each longitudinal edge of the casing 28 is a vertically adjustable scraper 32.

45 The invention includes a pair of outstanding trowels 33 having upstanding flanges 34 bearing against the scrapers 32. Securing devices of any desired sort, indicated at 35, pass through the flanges 34 of the trowels 33 through the scrapers 32 and engage with the casing 28. In order to provide for a 50 vertical adjustment of the scrapers 32 and the trowels 33, these elements are equipped with elongated vertical slots 36 clearly shown in Fig. 3 and coöperating with the securing devices 35 to bring about the result above mentioned.

55 Located partly within the contour of the casing 28 and shielded thereby is a pressure roller 25 having trunnions 26 which are journaled in the tubular shafts 29 of the casing 28.

60 To one of the trunnions 26 of the pressure roller 25 is secured a sprocket wheel 37 about which is trained a sprocket chain 38 engaged around a sprocket wheel 39 secured to one end of a shaft 40 journaled in the 65 standards 20.

It is contemplated that the shaft 40 shall be rotated first in one direction and then in an opposite direction, but since there are many mechanisms known in the mechanical art for producing the result above mentioned, no specific means to the end in view is shown.

Secured to the shaft 40 and preferably located adjacent the longitudinal center of the supporting structure is a drum 41.

70 A flexible element 42 is given a turn or two around the drum 41 and is passed about idlers 43 journaled on the supporting structure 1.

75 The extremities of the flexible element 42 are secured to the main carriage 5 as indicated at 44.

80 The operation of the structure is as follows:—The auxiliary carriage 9 in the first instance is located either on the auxiliary track 3 or the auxiliary track 4. While the carriage is thus positioned, the mold 12 is set up on the platform portion of the carriage. The main carriage 5 then is moved along the track 2 until the track 7 is adjacent the auxiliary track 3 upon which it will be presupposed that the auxiliary carriage 9 is located. Then the auxiliary carriage 9 is trundled off the track 3 onto the track 7 of the main carriage 5. By rotating the shaft 40 in opposite directions, the main carriage 5 through the medium of the flexible element 42 will be reciprocated on the main track 2 and with it will reciprocate the auxiliary carriage 9, the latter being held against movement with respect to the main carriage by means of the dogs 11 should such an operation be found necessary. When the function of the combined scraping and troweling means has been explained it will be obvious that when the carriages 9 and 5 are reciprocated, the material in the mold 12 will be smoothed off and be finished on its upper surface. After this finishing operation has been completed the carriage 9 may be wheeled off the carriage 5 onto the track 4 or the track 3, the carriage 5 first having been disposed adjacent that track upon which the auxiliary carriage is to be wheeled.

9885 9890 9895 9900 9905 9910 9915 9920 9925 9930 9935 9940 9945 9950 9955 9960 9965 9970 9975 9980 99

scrapers 32 may be tilted, so that these elements will coöperate properly with the material during both strokes of the main carriage 5. The trowel 33 and the scraper 32 5 may be held in adjusted positions with respect to the top of the mold 12 by engaging the latch mechanism 31 with the segment 27.

The material in the mold 12 first is compressed by the yieldingly depressed pressure roller 25, excess material is held back and scraped away by the element 32 and subsequently a finishing stroke is given to the upper surface of the material by the trowel 33 which may be resilient.

15 One advantage in using two superposed trucks is that the driving means, represented by the flexible elements 42, remain permanently connected with the main truck and do not have to be detached and reattached, as would be the case if but one truck or wheel mounted mold were used. The two superposed trucks are much heavier than the striking or troweling mechanism. Consequently, when the trucks are moved, the 20 same proceed steadily and the operation is much more uniform than is the case when the striking or troweling mechanism, being relatively light, is moved with respect to the truck.

30 Having thus described the invention, what is claimed is:—

1. In a device of the class described, a main track; a main carriage mounted to move on the main track; means for reciprocating the main carriage; an auxiliary carriage mounted to move on the main carriage and to move with the main carriage; a mold on the auxiliary carriage; an auxiliary track adapted to receive the auxiliary carriage from the main carriage when the auxiliary carriage is moved with respect to the main carriage; and a relatively fixed material engaging means coacting with the mold when the auxiliary carriage moves within 45 the main carriage.

2. In a device of the class described, a main track; a main carriage mounted to reciprocate on the main track; a mold mounted to move with the main carriage; a double-edged trowel; means for supporting the trowel intermediate its edges for tilting movement; and means for tilting the trowel to cause the edge portions thereof to come respectively into engagement with the mold 55 as the carriage and the mold are reciprocated.

3. In a device of the class described, a track; a carriage mounted to move along the track; a mold mounted to move with the carriage; a roller coacting with the mold; means for supporting the roller for rotation; mechanism for rotating the roller; mechanism for moving the carriage; and means for operating both of said mechanisms simultaneously.

4. In a device of the class described, a track; a carriage mounted to move along the track; a mold mounted to move with the carriage; a roller coacting with the mold; means for supporting the roller for rotation; a shaft, means for supporting the shaft for rotation; means for operatively connecting the shaft with the carriage to move the carriage; and means for operatively connecting the shaft with the roller to 70 rotate the roller.

5. In a device of the class described, a supporting structure including a track; a carriage mounted to move along the track; a mold mounted to move with the carriage; 80 a roller coacting with the mold; means for supporting the roller for rotation; a shaft journaled in the supporting structure; means for operatively connecting the shaft with the roller; a flexible element engaged 85 with the shaft and secured to the carriage, the flexible element being formed into oppositely extended loops; and spaced elements upon the supporting structure, about which elements the loops are engaged. 90

6. In a device of the class described, a track; a carriage mounted to move along the track; a mold movable with the carriage; means for moving the carriage; a roller coacting with the mold; a casing in 95 which the roller is journaled; means for supporting the casing tiltably; and material engaging means carried by the casing and coacting with the mold when the casing is tilted. 100

7. In a device of the class described, a supporting structure; a carriage mounted to reciprocate on the supporting structure; a mold mounted to move with the carriage; standards mounted on the supporting structure; bearings mounted to move in the standards; means for supporting the bearings yieldingly; a casing including tubular shafts journaled in the bearings; a roller comprising elements journaled in the tubular shafts and housed by the casing; means for rocking the casing in the bearings; a releasable connection between the said means and one bearing; and a material engaging means carried by the casing and coacting 115 with the mold. 110

8. In a device of the class described, a supporting structure; a carriage mounted to move along the supporting structure; a mold mounted to move with the carriage; 120 standards constituting a part of the supporting structure; bearings vertically movable in the standards; a casing comprising tubular shafts journaled in the bearings; a roller coacting with the mold and comprising trunnions journaled in the tubular shafts; a material engaging element coacting with the mold and carried by the casing; a lever connected with the casing; a segment on one bearing; a latch mechanism on the 125 130

lever and coacting with the segment; a shaft journaled in the supporting structure; means for operatively connecting the shaft with the carriage to move the carriage; and
5 means for operatively connecting the shaft with the roller to rotate the roller.

In testimony that I claim the foregoing

as my own, I have hereto affixed my signature in the presence of two witnesses.

FRED E. FLACK.
